DESIGN FOR A FRUIT REAMER

Joseph M. Majewski, Jr., Kansas City, Mo., assignor to Foster L. Talge, Kansas City, Mo., doing business as Rival Manufacturing Company

Application May 15, 1939, Serial No. 84,995

Term of patent 14 years

To all whom it may concern:

Be it known that I, Joseph M. Majewski, Jr., residing at Kansas City, in the county of Jackson and State of Missouri, have invented a new, original, and ornamental Design for a Fruit Reamer, of which the following is a specification, reference being had to the accompanying drawing, forming part thereof, in which

Fig. 1 is a perspective view of a fruit reamer, showing my new design.

Fig. 2 is a top plan view of the fruit reamer shown in Fig. 1.

Fig. 3 is a side elevation of the fruit reamer shown in Fig. 1.

Fig. 4 is a sectional view taken along the line 4—4, Fig. 2.

I claim:

The ornamental design for a fruit reamer, substantially as shown.

JOSEPH M. MAJEWSKI, JR.
